UNITED STATES PATENT OFFICE.

JACOB AIZENMAN, OF NEW YORK, N. Y.

DESIGN FOR A MANTEL-COVER.

40,371.

Specification for Design. Patented Nov. 23, 1909.

Application filed September 25, 1909. Serial No. 519,646. Term of patent 3½ years.

To all whom it may concern:

Be it known that I, JACOB AIZENMAN, a citizen of the United States of America, residing in New York, borough of Manhattan, county and State of New York, have invented a new, original, and ornamental Design for Mantel-Covers, of which the following is a specification, reference being had to the accompanying drawing, forming part thereof.

The figure represents a front elevation of a mantel-cover, showing my new design.

I claim:

The ornamental design for a mantel-cover, as shown.

JACOB AIZENMAN.

Witnesses:

PAUL GOEPEL,
J. A. CORK.
